ALFRED HOFMANN, OF PALISADE, NEW JERSEY

KNITTING MACHINE

Application filed June 12, 1930. Serial No. 460,643.

This invention relates to knitting machines, and more especially is an improvement in the mechanism of straight knitting machines such as are used for manufacture of full fashioned knitted hosiery or other fabrics. For the purpose of illustrating the principles of the invention it is shown applied to a knitting machine of the Cotton type, or a machine employing a number or banks of united needles of the spring beard type, each bank adapted for the production of the leg or foot of a stocking or other knitted product; there being a number of makes of such type of machine to which the invention is applicable.

The general object of the invention is to improve the action of the needles, jacks, sinkers and other elements cooperating therewith, more especially in a way to improve the product by eliminating the tendency to form undesired visible longitudinal stripes or streaks. A particular object is to improve the operation of the sinkers, their actuating means and the jacks, so as to avoid the defect in operation and product already mentioned. Other and further objects and advantages of the improvement will be pointed out in the hereinafter following description or will be apparent to those skilled in the subject. To the attainment of such objects and advantages the present invention consists in the novel knitting machine and the novel features of combination, cooperation and construction herein illustrated or described.

In the accompanying drawings Fig. 1, partly in vertical transverse section and partly in side elevation, shows a typical portion of a knitting machine of the class referred to, including the bearded needles, sinkers, dividers and associated parts, sufficient for the purposes of describing the present improvement, it being understood that standard machine may be referred to to supply other connections and parts not shown. Fig. 2 is a perspective view of a portion of Fig. 1. Figs. 3 and 4 are diagrams showing the relation of the thread, the needles, the sinkers and the dividers in two successive stages or positions wherein the present improvement is concerned.

In Fig. 1 of the drawings a bar, row or connected bank of bearded needles 5 is indicated, it being understood that the entire row or bar of needles is united or held in a common clamping or supporting member or bar, as in the class of machine referred to. The means for laying the thread upon the needles is not shown, as it may be of any well-known kind.

Cooperating with the needles is a row or bank of sinkers 7 of the sliding type, each of these having a notch 8 at its forward or needle end to engage and thrust the thread into preliminary loops and at the other end a butt 9 for cooperation with the actuating mechanism.

A bank of dividers 10 is shown each of which at its front or needle end has a notch 11 and at the other end a butt 12. The sinkers and dividers may be mounted above a supporting guide 14 above which is an overlying guide 15, the two guides being mounted at the top of a member or carriage 16 which may have movement or adjustment in accordance with the practise in the art. A thrusting member 18 is shown adapted to effect the advancing of the dividers at the proper time, and associated with it is a member 19 for retracting the dividers and the sinkers. For example the thrusting and retracting members may move forwardly to advance the dividers and then descend sufficiently to engage the butts of the sinkers and then retract to draw back the sinkers and dividers after the thread loops have been completed.

The sinkers are intended to be advanced prior to and independently of the dividers, and in fact successively along the bank of sinkers. For this purpose a series of sinker advancing means is shown, consisting typically of a bank of jacks 21 each arranged to engage the butt of a sinker and thrust it forward. Each jack is shown as having a nose 22 contacting directly with its sinker and at the other end a tail 23 spring pressed at either of its extreme positions. The entire bank of jacks may as usual be supported on a common pivot or rod 24 and the successive advancing movements of the jacks and sinkers may be brought about by a member or cam 100

- 25 which is adapted to move longitudinally of the machine so as to cam the jacks forwardly one at a time, as the sinker loops are formed and thread drawn from the supply.
- 5 The cooperation between the needles, sinkers and dividers is diagrammatically shown in Figs. 3 and 4. While the thread *a* is being laid longitudinally behind the bank of needles, the sinkers *7* are thrust forwardly 10 one at a time to produce a first set of loops *b* of excessive depth. The sinkers are shown as operating in this manner between every alternate pair of needles but the arrangement might be varied, so long as the sinkers 15 are spaced periodically, leaving unlooped stretches of thread at intervals between needles. After all of the first set of loops has been formed the dividers come into play, being thrust forward simultaneously as described 20 so as to bring about the formation of the remaining loops *c* as shown in Fig. 4, at the same time drawing back the loops *b* to their normal size, the sinkers *7* being held only yielding forward at this time to permit such drawing back of the first set of 25 loops.
- The resilient means tending to hold the jacks *21* and sinkers *7* in their advanced position, but permitting yielding retraction 30 as described, may comprise a bank of springs *27* pressing upon the jacks and thereby exerting their resilient pressure upon the sinkers. These are shown as long shank springs of the usual standard type, each of them having 35 its free end formed with an offset or hump at *28* grooved at its under or front side to maintain a pressing engagement upon the tail *23* of the corresponding jack, and each spring having at the other end a butt *29* by 40 which this end of the spring may be anchored or firmly held in a supporting member, block or bar *31* extending longitudinally of the machine and rigidly holding or clamping the lower or rear ends of the entire bank of 45 springs. Opposed to the supporting bar *31* is a clamping member or plate *32* interlocking with the bar and the two between them clamping the butt ends of the springs, the parts being held in clamped position by a 50 series of screws *33* placed at intervals along the length of the clamp plate and bar. It is understood that the supporting bar *31* may undergo any usual or desired movements during knitting operations.
- 55 In the knitting of stockings or other hosiery on machines of the class described it has been quite common or frequent to find the product is streaked or striped with irregular longitudinal effects due to some irregularity 60 in the knitting action. The stripes themselves are not regularly placed and cause a disfigurement of the work and a substantially reduced market value. It has been the effort for a long time to eliminate this defect and 65 produce hosiery uniformly free from the

streaks or stripes referred to. The reason for this defect noted has not been heretofore thoroughly understood and not overcome. On the supposition that irregularities in friction between the various elements may have caused the defect the attempt has been made to cure it by the application of oils or greases of different characters; which not only has not obviated the defect but has endangered the spoiling of the product by grease marks. 70 On the supposition that, despite high accuracy in the manufacture of the sinkers, dividers and cooperating parts, they have not been sufficiently exact and uniform to give uniformity of action along the length of the machine, effort has been made to increase the accuracy of manufacture of such parts, with consequent added expense but without overcoming the defect. 75

With this invention the discovery has been made that the defective action, and the production of the objectionable stripes, can be obviated by the introduction of means for modifying and rendering uniform the yielding resistance of the sinkers to the drawing back of the first set of loops while the dividers are producing the second set of loops. By reference to Figs. 3 and 4 it will be understood that if, in the yielding action of the sinkers, there is a difference of resistance, for example in one sinker as compared with an adjacent one, the product will not contain the uniform loops as indicated in Fig. 4, but will show a differentiation in regard to the ultimate size of the respective loops of the first set, due to the difference in retracting movement as just described, which difference may be continued through row after row, thus producing a longitudinal effect or stripe. 90

The present invention having been applied to the type of machine wherein the resisting springs act upon jacks which in turn act upon the sinkers, it is specifically the principle of the present improvement to modify the action of the spring pressed jacks upon the sinkers by rendering uniform the spring resistance of the entire banks of springs, jacks and sinkers, more especially during the dividing action, during which the first set of loops is drawn back to final size. There has therefore been devised and illustrated herein means cooperating with the bank of springs to render uniform the described yielding action, and at the same time the improved means preferably tends to render firmer the spring pressure and resistance upon each individual jack and sinker; all of which is accomplished without sacrificing the advantages of the long shank springs which have 105 become standard in this class of machine. 110

The supplemental element or improvement hereof may be described as a longitudinal contact member or strip or abutment arranged to contact or press upon the shanks 130

of all the springs of the sinkers, during the action of the dividers. This is preferably in the nature of a stiffly resilient strip 35 adapted along one line to contact the entire bank of jack springs, so as to reinforce and equalize the action of all of the springs.

While the contact member or strip member 35 might be mounted in various ways so long as it gives the desired contact and pressure upon all of the springs during the dividing action, the preferable and simplest arrangement is to mount and hold the contact strip in the same support or clamping means as the springs themselves. Thus the strip 35 is shown as having its lower or clamped end 36 mounted and confined between the supporting bar 31 and the clamp plate 32, in a position substantially adjacent to the springs, preferably at their back or upper sides, that is the sides opposite to the sides which apply the resilient pressure to the jacks and sinkers.

Preferably further the contact or pressure strip 35 does not lie contiguous to the springs over its entire width, but is shaped away from the springs beyond the clamp means, as clearly shown, and bent back or offset at the end 37 so as to afford a contact line 38, at which line the strip contacts, equalizes and reinforces the bank of springs. Preferably, and as shown, the contact line 38 is not merely at the back sides of the springs, but is at a point substantially midway of the length of the springs, by which is intended a point substantially removed from both the held ends and the free ends of the springs.

By this specific mode of embodiment of the improvement there is no need of introducing any structural change in the existing machines, the only change being the introduction of the spring contacting or reinforcing strip 35 into the spring holding clamp. This improvement has been demonstrated and found to give highly satisfactory results in the elimination of the undesired longitudinal stripes in hosiery. The particular embodiment as shown also is such as to permit, and not to interfere with, a slight play of each individual spring laterally of its own length, by sliding longitudinally upon the contact line of the strip 35, which is desirable. The disclosed arrangement also retains the advantage of the full flexibility of each spring from its held end to its free end. The usual action of the springs therefore is not impaired since each can flex over its whole length and can slide laterally of its length as described.

Various modifications of arrangement and combination may be made within the scope of the invention. The contact strip 35, while preferably composed of brass or copper, and fairly thin so as to be stiffly resilient, might be perfectly rigid. As preferred but not broadly essential details the contact strip 35

is shown mounted on the same supporting bar that holds the springs 27; and is in operative contact with the springs, not only while they are controlling the jacks and sinkers during the advance of the dividers, but at all times.

Having described a knitting machine embodying the present invention it is pointed out that the principles thereof may be variously embodied and that the claims are not intended to be limited to details of structure or arrangement except to the extent set forth therein.

What is claimed is:

1. In a knitting machine of the type having the following well known elements, the series of bearded needles on which the successive courses of thread are laid and loops formed, the series of sinkers operable successively to force the thread into periodic or alternate spaces between needles to form a first set of loops of excess depth and to hold them yieldingly, the series of dividers operable unitedly, following the operation of the sinkers, to force the thread into the remainder of the spaces between needles thereby to form the remaining loops and draw back the first set of loops, the series of spring holding devices adapted to press the sinkers toward loop holding position, including long-shank springs, one for each sinker, arranged to apply resilient resisting pressure upon the sinkers; the combination, with such elements, of a longitudinal support or block holding the butt ends of all the springs, and a supplemental member or strip arranged to contact and press equally upon the midportions of the shanks of all the springs, during the operation of the dividers, to control or ensure uniformity of the yielding resistance to the drawing back of the first set of loops, and thereby uniformity of the loop structure of the knitted product.

2. In a hosiery knitting machine of the straight type, in combination, the united bank of needles on which the successive courses of thread are laid and loops formed, the series of sinkers operable successively to form a first set of loops, the series of dividers operable together to form a second set of loops and to draw back the first set of loops, the series of jacks cooperating with the sinkers to move and hold them in loop holding position, the series of long-shank jack springs, one for each jack, arranged to apply resilient pressure upon the jacks, and thereby upon the sinkers, to permit their retraction during the operation of the dividers, a support or bar holding the butt ends of all the jack springs, and a longitudinal contact member or abutment, arranged to contact upon the shanks of all the springs, during the action of the dividers, to modify and render uniform the yielding resistance of the sinkers to the drawing back of the first set of loops.

3. A knitting machine as in claim 1 and wherein the contact member is arranged in constant contact with all the springs along a longitudinal line, and is formed with a longitudinal contact edge along which each spring may independently slide laterally of its own length.
4. A knitting machine as in claim 2 and wherein the contact member consists of a longitudinal strip itself possessing resilience reinforcing that of the respective springs along a line between the held and free ends of the springs.
5. In a knitting machine of the kind referred to, in combination with the series of sinker jacks, the series of long-shank jack springs, one for each jack, arranged to apply resilient pressure upon the jacks, and thereby upon the sinkers, and a supporting bar holding the butt ends of all the jack springs; a longitudinal contact member, arranged to contact upon the shanks of all the springs, at a point between their held and free ends, to modify and render uniform the yielding resistance of the jacks and sinkers.
6. A machine as in claim 5 and wherein the contact member is a strip in constant contact upon the springs and constructed to allow sliding play of the springs along the contact line.
7. A machine as in claim 5 and wherein the contact member is a strip in constant contact upon the springs and constructed to allow sliding play of the springs along the contact line, and said strip being mounted and held in the same supporting bar as the springs.
8. In a knitting machine of the kind referred to, in combination with the series of sinker jacks, the series of long-shank jack springs, one for each jack, arranged to apply resilient pressure upon the jacks, and thereby upon the sinkers, and a supporting bar clamping the butt ends of all the jack springs; a longitudinal contact member, arranged to apply a constant reenforcing contact equally upon the shanks of all the springs, at a contact line between their held and free ends, and at their sides opposite to their pressure upon the sinkers.
9. A machine as in claim 8 and wherein the springs are free to flex both between the contact line and their free ends, and the contact line and their clamped ends.
10. A machine as in claim 8 and wherein the springs are free to flex both between the contact line and their free ends, and the contact line and their clamped ends, and the contact member is itself a stiffly resilient longitudinal strip.

In testimony whereof, this specification has been duly signed by:

ALFRED HOFMANN.
